United States Patent Office

Des. 191,484
Patented Oct. 3, 1961

191,484

DISPLAY RACK

Joseph A. Bardo, 10130 Gerard Way, and John L. Ventimiglia, 1293 Farringdon Drive, both of San Jose, Calif.

Filed July 28, 1960, Ser. No. 61,562

Term of patent 14 years

(Cl. D80—10)

FIG. 1 is a front perspective view taken from the top and to one side of a display rack embodying our new design;

FIG. 2 is a top plan view thereof; and

FIG. 3 is a side elevational view thereof.

We claim:

The ornamental design for a display rack, as shown.
